CONNECTING CLIP

Ralph S. Mueller, Cleveland, and Scott Mueller, Shaker Heights, Ohio, assignors to Mueller Electric Company, Cleveland, Ohio, a partnership, composed of Ralph S. Mueller, Maude K. Mueller, Virginia de Coningh, and Scott Mueller

Application August 1, 1934, Serial No. 737,956

1 Claim. (Cl. 173—273)

This invention relates to an electrical connecting clip of the hinged jaw type.

An object of the invention is to provide an electrical connecting clip of the hinged jaw type which is so constructed that it may be readily and economically assembled and when so assembled will have its jaws maintained in the proper relationship and the danger of said jaws twisting or becoming relatively offset will be reduced to a minimum.

Another object is to provide an electrical connecting clip of the hinged jaw type wherein the hinged connection between the clip members may be economically and positively made, the clip members may be interlocked to prevent relative twisting or offsetting thereof, and said members will have the desired and necessary strength to properly perform their functions.

A further object is to provide a clamp member of the character above specified and having elongated thin jaws to enable the clip to be applied in inaccessible places, such as are found in radios and the like, and which possesses the advantages above enumerated and additionally, has the advantage that the elongated thin jaws are so formed as to have sufficient strength to resist the torsional, bending, and other strains and stresses to which they are subjected, because of their extreme length.

Further objects and advantages residing in the invention will become apparent hereinafter during the detailed description of two embodiments thereof which is to follow.

In the accompanying drawing are illustrated the two embodiments of the invention above enumerated.

Fig. 1 is a side elevational view of a connecting clip embodying the invention.

Fig. 2 is a top plan view of the clip shown in Fig. 1.

Fig. 3 is a detailed sectional view taken substantially on line 3—3 of Fig. 1, looking in the direction of the arrows.

Fig. 4 is a detailed sectional view taken substantially on line 4—4 of Fig. 1, looking in the direction of the arrows.

Fig. 5 is a side elevational view of a different form of clip from that shown in Figs. 1 to 4 inclusive, and also embodies certain aspects of the invention.

Fig. 6 is a detailed sectional view taken substantially on line 6—6 of Fig. 5 looking in the direction of the arrows; and

Fig. 7 is a top plan view of the clip shown in Fig. 5.

The electrical connecting clip shown in Figs. 1 to 4, inclusive, is provided with elongated relatively narrow jaws to enable the clip to be applied at points which are inaccessible to the ordinary short jawed clip. Clips of this type are frequently required in making connections in radios and the like. The clip comprises two clip members 10 and 11, preferably formed of sheet metal stampings. The clip member 10 is provided with a rearward extension 12 having formed thereon a tubular and longitudinally split portion 13 through which the electrical conductor extends. The member 10 forwardly of the extension 12 is provided with an opening into which is screwed a binding screw 14 which may clamp the end of the conductor to the clip in electrical contact therewith if the conductor used is an insulated wire. If a conductor having a terminal such as the so-called "banana" terminal is used, the terminal is merely inserted in the barrel and makes contact by the spring action of the terminal itself.

The members 10 and 11 are provided at their forward ends with elongated relatively narrow jaws 15 and 16, later to be referred to more in detail. The member 10 just forwardly of the binding screw 14 is provided with a pair of openings 17 forming a part of the hinge connection between the members 10 and 11. The member 11 at its rear end is provided with a portion 18 of reduced width and having spaced narrow extensions 19 at the end thereof, which, when the members are assembled, pass through the openings 17 in the member 10 and are clinched beneath the member, as clearly illustrated in Fig. 1 to form an economical hinged connection between the members. The members 10 and 11 are provided with crossed portions 10^a and 11^a which are interlocked against substantial relative lateral movement, while permitting the pivotal movement of the member in the manner now to be described. The portion 10^a of the member 10 is of reduced width with respect to the width of the remainder of the member and passes through a slot 20 in the portion 11^a of the member 11, the width of said slot being such as to receive the portion 10^a and allow the same to have a free longitudinal movement therein but restraining the portion 10^a against substantial lateral movement.

The interlock between the portions or necks 10^a and 11^a in addition to preventing excessive relative lateral movement between the clip members, also acts to facilitate the formation of the hinged connection between the members. In the

prior clips wherein the crossed neck portions of the clip members were not interlocked, it was necessary to form the hinge connection between the members very accurately and to have such connection impart a relative twisting movement to the clip members to bring and to retain the jaws of said members in the proper relationship. This was accomplished by having the openings 17 arranged slightly out of transverse alignment 10 or offset so that when the extensions 19 were passed therethrough and clinched in position, a force would be exerted upon the clip members setting up a relative twisting movement therebetween which acted to bring the jaws into the proper position. It was necessary, because of this misalignment or offset condition of the openings 17, to form such openings very accurately, not only as to their relative positions, but also with respect to their size in order that the proper 20 amount of relative twisting movement would be imparted to the members to bring the jaws thereof into the correct relative position. The use of the interlock between the necks or crossed portions of the clip members, obviates to a large degree the necessity of forming the openings 17 and the extensions or projections 19, so accurately, since even if there is a slight play of the extensions 19 in the openings, the interlocked crossed portions or necks of the members act to maintain the jaws in the proper relative position, hence the interlock cooperates effectively with the hinge construction to reduce the cost of manufacture and facilitate the assembly of the clip members, as well as to maintain the jaws in the desired position during use and to prevent excessive twisting or offsetting of the same. This last feature is important when it is remembered that clips of this character are generally applied to a post with a twisting action, so as to cause 40 the teeth of the jaws to dig into the post.

Inasmuch as the member 10 is provided with a very narrow reduced portion or neck 10^a having a connection with the remainder of the member which forms a weakened zone, it is imperative 45 that means be provided to strengthen not only the member as a whole, but particularly the portion 10^a thereof and the point of connection between said connection and the remainder of the member. Therefore, the member 10 is provided 50 along its longitudinal edges with flanges 21 which extend from rearwardly of the binding screw 14 the full length of the member and partly along the jaw 15 thereof to the point 22. The member 11 is similarly provided along its longitudinal 55 edges with strengthening flanges 23 which extend from the reduced portion 18 of the member to the point 22 on the jaws 16, the points 22 on the jaws 15 and 16 lying in alignment or one above the other.

60 The flanges 21 and 23 impart the desired and necessary strength to the members and particularly to the portion 10^a of the member 10 at its point of connection to the member. At the points 22 on the jaws 15 and 16 the flanges 21 and 23 65 are turned in the reverse direction and form inwardly extending flanges 21^a and 23^a extending toward each other and having adjacent their outer ends interengaging toothed portions forming the gripping parts of the jaws. The jaws 15 and 16 taper inwardly in width from the points 22 and merge into narrow elongated portions at their outer ends, such narrow elongated portions being substantially coextensive in length 70 with the toothed portions of the flanges 21^a and 75 23^a, as is clearly shown in Figs. 1 and 2.

It will be noted that the extreme length and narrowness of the jaws 15 and 16, together with the remoteness of the hinge connection between the members 10 and 11 act, during the use of the clip, to subject the jaws to substantial torsional, bending and shearing strains and stresses and, therefore, means must be provided to give the jaws sufficient strength to resist such strains and stresses. To this end the jaws 15 and 16 are transversely arched, as indicated at 24 in Fig. 3, it being noted that the arched section is the full width of the clip.

The transversely arched cross-section of the jaws 15 and 16, in combination with the flanges 21, 21^a and 23, 23^a, impart to the jaws the desired 15 strength and rigidity to effectively withstand the strains and stresses to which they are subjected during the use of the clip, while the interlock between the portions 10^a and 11^a prevents excessive twisting or offsetting movement of the jaws 20 and allows the hinge connection between the members to be located at a point remote from the jaws.

A coiled spring 25 arranged between the members 10 and 11 serves to hold the jaws in close biting engagement, as is well understood.

The clip shown in Figs. 5 to 7 inclusive, is constructed substantially the same as that shown in Figs. 1 to 4, inclusive, with the exception that its jaws are not of the elongated narrow type, 30 but are relatively broad and short. It is not believed necessary to explain in detail the construction of the second embodiment of the invention, since it corresponds exactly to that above described, with the exception of the jaws as mentioned and with the further exception that the rear extension 12 is provided with ears 26 which may be clinched around the conductor. The jaws 15^a and 16^a of the second embodiment, as previously stated, are relatively short and it will 40 be noted that they are not provided with flanged portions corresponding to the flanged portions 21^a and 23^a of the first described embodiment, but that the flanges 21 and 23 of the members 10 and 11 do extend along the jaws 15^a and 16^a 45 substantially to the outer end thereof. The outer end of the jaws 15^a and 16^a are provided with down turned toothed portions 27, there being no toothed portion along the side of the jaws.

The clip shown in Figs. 5 to 7, inclusive, may be advantageously used for forming any connections located at points easy of access.

Although specific embodiments of the invention have been illustrated and described herein, 55 it should be understood that the invention is susceptible of such variations and modifications as fall within the scope of the appended claim.

Having thus described our invention, we claim:

An electrical connection clip composed of two 60 channeled pivotally connected members having interlocked portions provided with elongated relatively narrow jaws at their forward ends of transverse arched cross-section, the interlocked portion of one of said members being relatively 65 narrow with respect to the width of the member and extending through an elongated slot in the portion of the other member, one of said members having a rearward extension to receive an electrical conductor, the flanges of both channeled members being continued forwardly along and beyond the interlocked portions thereof and then reversed and extended along the jaws and having interengaging toothed portions, the flanges 70 of one of said members being continued rear- 75

wardly past the pivot point and partway along said extension, said last named member having adjacent said extension and between the flanges thereof a slot and said other channeled member having an end portion fitting between the flanges of the last named member and provided with a lug extending through said slot and bent against

said last named member to form the pivotal connection between the members, and a spring between said members to normally hold the said jaws closed.
